UNITED STATES PATENT OFFICE.

LOUIS HOLZWORTH, OF NEW YORK, N. Y., ASSIGNOR TO THE EAGLE PENCIL COMPANY, OF SAME PLACE.

PEN-HOLDER.

SPECIFICATION forming part of Letters Patent No. 399,043, dated March 5, 1889.

Application filed December 3, 1888. Serial No. 292,467. (No model.)

To all whom it may concern:

Be it known that I, LOUIS HOLZWORTH, of the city, county, and State of New York, have invented a new and useful Improvement in 5 Pen-Holders, of which the following is a specification.

The object I have in view is to produce a pen-holder capable of receiving and fitting pens of various sizes and shapes. It is well 10 known that pens vary considerably, not only in the size, but in the shape of that part of them which is inserted in the slot of the pen-holder. This part has a much sharper transverse curve in some pens than in others, and 15 consequently a pen-holder which will fit some pens is not at all well adapted to receive and hold others. To remedy this difficulty I have devised a new pen-holder which is cheap and durable, can be easily made, and is entirely 20 efficient. This pen-holder consists, essentially, of a "barrel," combined with a plurality of sheet-metal strips or tongues curved concentrically with the barrel and placed inside of said barrel concentrically, one within the 25 other, thus furnishing a series of pen-slots, the transverse curvatures of which become sharper and more pronounced as they approach the common center. I prefer that each of these strips should be formed with a 30 barrel or tubular portion, which portion fits the one within the other and surrounds the end of the pen-handle, the external or main barrel surrounding them all. In this way the parts can be easily secured together and 35 to the pen-handle.

In the accompanying drawings, Figure 1 is an elevation, and Fig. 2 is a longitudinal central section, of a pen-holder embodying my invention. Fig. 3 is a like section of a modification.

A is the pen-handle, and B is the external or main barrel of the pen-holder. I prefer to make this barrel of hard rubber and to fit it upon a tenon of the pen-handle, so that the 40 exterior of the barrel shall be flush with and shall form in effect a continuation of the exterior surface of the handle.

C shows the sheet-metal tongues or strips placed inside the barrel B and concentrically one within the other. There are three of 50 these tongues in the present instance, and by them, in conjunction with barrel B, are formed three pen holding or receiving slots. By prolonging the tenon A' of the handle, as seen in Fig. 3, so that it shall come opposite the innermost tongue, a fourth slot is provided. I prefer to make these tongues progressively shorter at their outer ends as they approach the center, as shown in the drawings, so that the user may select any one of the pen-slots 55 without difficulty. I also prefer to form each of these tongues at its inner end with a tubular portion, C'. These parts C' are nested within the outer or main barrel, B, and clasp one another tightly, and the innermost one 60 clasps the tenon A' of the handle. They can be secured together in this position by a small rivet or by any suitable means employed by mechanics for like purpose. The tongues C, being of thin sheet metal, take up but little 65 room, and the pen-slots formed by them are separated so little that when the pen-holder is in use it is difficult to determine in which slot the pen is inserted.

Having described my improvement, what I 70 claim herein as new and of my own invention is—

1. A pen-holder consisting, essentially, of the external or main barrel, B, and a plurality of curved sheet-metal strips or tongues, C, 75 nested and secured within said barrel concentrically with one another, as and for the purpose shown and described.

2. The pen holder and handle consisting of the external barrel, B, and the tongues C, provided with tubular inner ends, C', nested within the barrel and around the tenon of the handle A, as and for the purpose set forth.

In testimony whereof I have hereunto set my hand this 19th day of November, 1888.

LOUIS HOLZWORTH.
